UNITED STATES PATENT OFFICE.

ANTONIO CHIARELLI, OF NEW YORK, N. Y.

MONORAIL SYSTEM.

Application filed March 20, 1925. Serial No. 16,935.

This invention relates to improvements in railway systems, particularly of the monorail type, and it is the principal object of my invention to provide a monorail road 5 ensuring the utmost safety of travel and allowing the transportation of a considerable number of passengers in a limited number of cars.

Another object of the invention is the provision of a monorail railway system including devices for safely guiding the cars around curves, and one which can be operated by electric, steam or any other source of power.

15 A further object of the invention is the provision of a monorail railway system using cars of the double-deck type and including novel means for coupling two cars together, the superposed cars as well as the 20 adjoining cars on the same level.

A still further object of the invention is the provision of a monorail railway system having novel and improved means for switching the cars from one rail to another 25 and for braking the cars quickly and effectively to hold them instantaneously.

These and other objects and advantages of my novel railway system will become more fully known as the description thereof 30 proceeds, and will then be specifically pointed out in the appended claims.

In the accompanying drawings forming a material part of this disclosure:

Fig. 1 is a perspective view of a monorail 35 railway system constructed according to the invention, showing two cars of the system traveling in opposite directions.

Fig. 2 is a longitudinal vertical section through one car of the system.

40 Fig. 3 is a cross-section through one of the cars along line 3—3 of Fig. 2.

Fig. 4 is an elevation of a car of a modified type.

45 Fig. 5 is a sectional detailed view of the buffer arrangement.

Fig. 6 is a detail sectional side elevation of a swivel wheel used for safely guiding a car on its rail around curves, etc.

50 The tracks 10 of the improved monorail railway system according to the invention have substantial triangular cross-sections

and are supported on posts 11 of any suitable material and height, set at suitable intervals along the right of way of the road. Parallel to and at a certain distance beneath 55 the monorail 10, a guard rail 12 is carried by the posts 11 for a purpose hereafter more fully to be described.

The cars used with the system are preferably of the double deck type, the upper section 13 and the lower section 14 are both equipped with a plurality of seats 15 of the customary type, windows 16 and entrance and exit doors 17 and 18 arranged in any suitable and required number either in the 60 center or at the ends of a car allowing simultaneous leaving and boarding of passengers on the elevated superposed platforms.

The lower section has end vestibules for the operator controllers, etc., and at the 70 center the car ends are formed like chambers 19, the walls of which form the bearings for shafts 20 of wheels 21 of the pulley type running on top of the rails 10.

Other chambers 22 and 23 are located at 75 both sides of chamber 19 and are equipped with platforms 24 and 25 respectively in which bearings are formed for the vertically arranged stubshafts 26 and 27, carrying upper guide roller blocks 28 on top of platforms 24 and 25, and extending through slots 29 in platforms 24 and 25. The lower ends of the shafts 26 and 27 are journaled in the bottom part of lower section 14 and carry above the same rollers 30 and 31 80 85 adapted to engage the guide rails 12 from opposite sides.

The guide roller blocks 28 carry each at its outer face, a rod 32, to which a piston 33 is attached working in a horizontally disposed cylinder 34 against the action of a spring 35 within the cylinder. The outer end of the spring is secured to a plate 36 within the cylinder to which a pin 37 is attached, extending through the end wall 95 of the cylinder and being threaded, carries an adjusting nut 38 or the like permitting the regulation of the spring tension within certain limits. A similar arrangement is made at the lower end of shafts 26 and 27 100 between and below car bottoms. In order to allow passengers to pass from the upper

to the lower section of the car, the stairs 39 and 40 are provided located in approximately the middle of each car.

In order to guide the wheels 21 safely around the curves in the track 10, the wheels 21 and their housings are constructed to swivel around vertical pins 41 passed through the wheel housing at their upper and lower ends, while their middle parts 19 extend through a boss 42 formed in the car frame.

The connection between each two cars must also be such as to allow a safe rounding of the curves, and for this purpose the 15 ends of the cars overlap in the manner indicated in Fig. 2 at 43 and carry at their extreme outer ends bellows 44 or the like to effect a tight closure. In order to facilitate any relative movement of the two adjoining cars, a plurality of rollers 45 are 20 arranged in the space between the tops of the two cars, while strong spiral springs 46 take care of, or absorb any shocks developed during the turning movement when taking 25 a curve.

The cars are equipped with the customary signal lights 47 near their tops and may be ventilated and lighted in any suitable well-known manner.

30 In Fig. 4 a modification of a car used with my improved monorail system is shown, car 48, of which has a chamber 49 formed therewith at its center, the walls of which carry a shaft 50 for the pulley roller 35 or wheel 51 in the groove of which engages the apex of the triangular rail 52 supported on posts 53 which support also a guide rail 54 at a distance underneath rail 52 and parallel thereto.

40 To the bottom of the car 48 the frames 55 and 56 are attached at opposite sides of the rail 52 and carry at their lower parts platforms 57 and 58 respectively. These platforms have journaled therein vertically arranged shafts 59 and 60 respectively which carry at their upper ends the guide rolls or blocks 61 and 62 constructed as in the preferred form to work with their rods in spring cylinder in the same manner 45 as described with my preferred form.

Between the platforms 57 and 58 the shafts 59 and 60 carry rollers 63 and 64 adapted to engage the guide rail 54 from opposite sides, while their lower ends carry 55 a pair of rollers or blocks, similar to the blocks 61 and 62 and cushioned in the same manner.

It will be clear that my improved monorail system will eliminate a great number 60 of wheels, tracks, noise, resistance and part of its energy and allow the trains to acquire a very great speed if desired.

Furthermore, by a special construction 65 of its cars, the system will carry a great number of passengers in one or more cars

and by using only one elevated rail, will prevent danger of crossings.

Yet the construction of my system is so simple that lots of material could be saved for its support and in case of towns where 70 it might be used, will free the streets from much structure, giving more light, air and sight.

The construction of one track and pillars instead of dirt, cut stones and cut sections of wood transverse and other material now used, will be more economical and by its solid base (which may be concrete) 75 can be placed anywhere, even in the un-leveled ground, sand or mud.

Wood beams reinforced if necessary with T metal bars or metal tubings, concrete or any other strong building material, can be used for the supporting of the metal rail.

80 A suitable number of doors 70 are provided in the bottom of the lower platform of the car through which suitable ladders may be lowered for the passengers to descend in case of emergency.

85 It is to be understood that such changes may be made in the general arrangement or the construction of the minor details of my system as fall within the scope of the appended claims, without departure 90 from the spirit of the invention.

Having thus described my invention, what I claim as new, and desire to secure by Letters Patent is:

1. Monorailway system comprising a monorail, posts for supporting said rail 100 above the ground, a guard or guide rail carried on said posts below said monorail and parallel thereto, a pivotally mounted pulley wheel on cars running over said monorail adapted to engage the apex of 105 said monorail, means for safely guiding said car along the guide rails around curves, bellows connecting the telescoping ends of two adjoining cars of a train, and rollers and springs for absorbing shocks.

110 2. In a monorail railway system of the class described double deck cars, a monorail of substantially triangular cross-section, a guide rail therebelow, a grooved wheel carried by the upper deck of said cars and pivotally secured in the frame thereof, adapted to run with its groove in engagement with the apex of said monorail over the latter, a means carried by each car for safely guiding said cars around curves in the track, a bellows connecting a pair of adjoining, partly telescoping cars of a train, a plurality of rollers between the tops of the telescoping car ends, and a plurality of 115 springs between the side walls of the telescoping car ends for absorbing shocks.

120 3. Monorailway system comprising a monorail, posts for supporting said rail above the ground, a guard or guide rail carried on said posts below said monorail 125

and parallel thereto, a pivotally mounted rotatable pulley wheel on cars running over said monorail adapted to engage the apex of said monorail, means for safely guiding said car along the guide rails around curves, bellows connecting the telescoping ends of two adjoining cars of a train, and rollers and springs for absorbing shocks.

4. Monorailway system comprising a 10 monorail, posts for supporting said rail above the ground, a guard or guide rail carried on said posts below said monorail and parallel thereto, a pivotally mounted pulley wheel supported by its housing constructed 15 to swivel around a pintle pin passed through the wheel housing at the upper and lower ends, while the middle part extends through a boss on cars running over said monorail adapted to engage the apex of said monorail, 20 means for safely guiding said car along the guide rails around curves, bellows connecting the telescoping ends of two adjoining cars of a train, and rollers and springs for absorbing shocks.

5. Monorailway system comprising a 25 monorail, posts for supporting said rail above the ground, a guard or guide rail carried on said posts below said monorail and parallel thereto, a pivotally mounted pulley 30 wheel on cars running over said monorail adapted to engage the apex of said monorail, means for safely guiding said car along the guide rails around curves, bellows connecting the telescoping ends of two adjoining cars of a train, and rollers supported from the top and bottom of the outer 35 telescoped cars and springs for absorbing shocks.

6. Monorailway system comprising a 40 monorail, posts for supporting said rail above the ground, a guard or guide rail carried on said posts below said monorail and parallel thereto, a pivotally mounted pulley 45 wheel on cars running over said monorail adapted to engage the apex of said monorail, means for safely guiding said car along the guide rails around curves, bellows connecting the telescoping ends of two adjoining cars of a train, and rollers supported from the top and bottom of the outer 50 telescoped cars and springs between the telescoped sides of the cars for absorbing shocks.

7. Monorailway system comprising a 55 monorail, posts for supporting said rail above the ground, a guard or guide rail carried on said posts below said monorail and parallel thereto, a pivotally mounted pulley 60 wheel on cars running over said monorail adapted to engage the apex of said monorail, means for safely guiding said car along the guide rails around curves, bellows connecting the telescoping ends of two adjoining cars of a train, and rollers supported from the top and bottom of the outer 65

telescoped cars and sprial springs between the telescoped sides of the cars for absorbing shocks.

8. In a monorail railway system of the class described double deck cars, a monorail 70 of substantially triangular cross-section, a guide rail therebelow, a grooved rotatable wheel carried by the upper deck of said cars and pivotally secured in the frame thereof, adapted to run with its groove in engagement with the apex of said monorail over the latter, a means carried by each car for safely guiding said cars around curves in the track, a bellows connecting a pair of adjoining partly telescoping cars of a train, a plurality of rollers between the tops of the telescoping car ends, and a plurality of springs between the side walls of the telescoping car ends for absorbing shocks.

9. In a monorail railway system of the class described double deck cars, a monorail 80 of substantially triangular cross-section, a guide rail therebelow, a grooved rotatable wheel carried by the upper deck of said cars and pivotally secured in the frame thereof by a pintle pin extending through upper and lower sides of said wheel housing and through a boss in said frame, adapted to run with its groove in engagement with the apex of said monorail over the latter, a means carried by each car for safely guiding said cars around curves in the track, a bellows connecting a pair of adjoining partly telescoping cars of a train, a plurality of rollers between the tops of the telescoping car ends, and a plurality of springs between the side walls of the telescoping car ends for absorbing shocks.

10. In a monorail railway system of the class described double deck cars, a monorail 90 of substantially triangular cross-section, a guide rail therebelow, a grooved rotatable wheel carried by the upper deck of said cars and pivotally secured in the frame thereof by a pintle pin extending through upper and lower sides of said wheel housing and through a boss in said frame, adapted to run with its groove in engagement with the apex of said monorail over the latter, a means 95 carried by each car for safely guiding said cars around curves in the track, a bellows connecting a pair of adjoining partly telescoping cars of a train, a plurality of rollers 100 between the tops and bottoms of the telescoping car ends, and a plurality of springs between the side walls of the telescoping car ends for absorbing shocks.

11. In a monorail railway system of the class described double deck cars, a monorail 105 of substantially triangular cross-section, a guide rail therebelow, a grooved rotatable wheel carried by the upper deck of said cars and pivotally secured in the frame thereof by a pintle pin extending through upper and lower sides of said wheel housing and 110

through a boss in said frame, adapted to run with its groove in engagement with the apex of said monorail over the latter, a means carried by each car for safely guiding said cars around curves in the track, a bellows connecting a pair of adjoining partly telescoping cars of a train, a plurality of rollers

between the tops and bottoms of the telescoping car ends, and a plurality of helical springs between the side walls of the telescoping car ends for absorbing shocks. ¹⁰

In testimony whereof I have affixed my signature.

ANTONIO CHIARELLI.
